UNITED STATES PATENT OFFICE

104,420

DESIGN FOR A DRESS

Irving A. Winter, New York, N. Y.

Application April 9, 1937, Serial No. 68,652

Term of patent 3½ years

To all whom it may concern:

Be it known that I, Irving A. Winter, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The gores on the skirt portion of the dress extend from the bodice portion of the dress in the front, and from the waistline portion in the rear.

I claim:

The ornamental design for a dress, substantially as shown, and described.

IRVING A. WINTER.
